Inventor:

UNITED STATES PATENT OFFICE.

ALFRED J. ALLEN, OF ESSEX, CANADA, ASSIGNOR TO CHARLES A. GOULD,
OF NEW YORK, N. Y.

CAR-COUPING.

SPECIFICATION forming part of Letters Patent No. 472,245, dated April 5, 1892.

Application filed September 5, 1891. Serial No. 404,817. (No model.)

To all whom it may concern:

Be it known that I, ALFRED J. ALLEN, a subject of the Queen of Great Britain, residing at Essex, in the county of Essex and Province of Ontario, Canada, have invented certain new and useful Improvements in Car-Couplers, of which the following is a specification, reference being had therein to the accompanying drawings.

10 This invention relates to new and useful improvements in car-couplers of that class known as a "vertical-plane" coupler; and it consists in the peculiar construction of a draft-bar, the coupler-hook, and the means for coupling and uncoupling said hook, and, further, in the peculiar construction, arrangement, and combination of the various parts, all as more fully hereinafter described.

In the drawings, Figure 1 is a detached plan view of one of my couplers. Fig. 2 is a horizontal central section thereof. Fig. 3 is a vertical central section. Fig. 4 is a side elevation. Fig. 5 is a cross-section through the coupling-head on line $x x$, Fig. 1. Fig. 6 is a detached side elevation of a locking-dog. Fig. 7 is a detached side elevation of the coupling-hook with the locking-dog shown in dotted lines as in the uncoupled position.

This coupler is of the general description 20 of the well-known vertical-plane coupler, consisting of the draw-bar A, having an open jaw at its outer end, consisting of the arms $a b$ upon opposite sides thereof, with a coupling-hook B pivoted in the outer end of the arm b . 25 This hook has the usual locking-arm C, adapted to be moved into parallelism with the draw-bar in a cavity or chamber D, formed in the arm b of the draw-bar.

In previous constructions of such couplers 30 the pivot-pin E, upon which this coupling-hook turns, has been inserted loosely in the socket formed in the arm b , the coupling-hook turning loosely upon that pin. In my coupler I preferably make an aperture entirely through 35 the arm b of the jaw for the pin E and secure that pin in position by means of a bolt or locking-pin F, as shown in Figs. 2 and 4, so that the pin turns with the jaw instead of turning on it. The object of this is twofold: 45 First, it enables me to secure a crank-arm G

to the lower end of the pin E, by means of which I can (with suitable connections extending to the side of the car) open the coupling-hook without going between the cars. The second object of this arrangement is that in 55 ordinary construction the pin rotates more or less at the same time that the coupling-hook turns about the pin, thus making an unnecessary amount of labor, due to the friction in handling the hook.

60 c are shoulders formed at the junction of the arm C and the coupling portion of the coupling-hook, which shoulders are adapted to strike flat bearings d , formed on the arm b of the draft-bar, as plainly shown in Fig. 1, 65 also constructed so that the shoulder c will take the blow from the locking-arm C of the hook when the cars come together in the act of coupling. This enables me to greatly reduce the weight of my coupling-hook and take the 70 strain almost entirely off of the locking-arm of the hook.

H is a locking-latch pivoted upon the pin J, which is secured in transverse apertures through the draft-bar, being headed at both 75 ends to hold it in position. This pin moves vertically in the central cavity of the draw-head and is adapted to be operated by means of a link I', secured to a pin J, arranged across a recess K in the top of the latch, as plainly 80 shown in Fig. 3. The upper end of this link is guided by bearings L in an extension M of the draw-head and connected to suitable operating mechanism N, extending to the side of the car, by means of which this latch may 85 be raised or lowered. This connecting mechanism may be of any desired construction.

The locking-latch is provided on its under side with an inclined bearing O, adapted to engage with the top of the locking-arm C of 90 the coupler, so that but a small amount of lift is required to release the dog from the locking-arm, the movement of the arm itself engaging with this inclined bearing being sufficient to lift the latch as soon as the point 95 P of the latch has been lifted to the top of such locking-arm. This locking-latch remains on top of the extension Q of the locking-arm while the hook is in its uncoupled position, and as soon as it has returned to the 100

position shown in Fig. 1 it will fall by gravity in front of the locking-arm and prevent the jaw from rotating on its axis to its uncoupled position.

5 What I claim is—

1. In a car-coupler, the combination, with the draw-head, of a vertically-swinging latch in the draw-head, having an inclined bearing on its under face, a pivoted coupling-hook on the draw-head, a reduced right-angled extension on the inner end of the hook, arranged to support the latch when in an opened position and to engage the inclined bearing when the coupler is to be uncoupled, and means for

raising the latch onto the extension, substantially as described. 15

2. In a car-coupler, the combination, with the draw-head, of a vertically-swinging latch, a pivoted coupling-hook, and a lateral extension on the hook supporting the latch when the coupling-hook is thrown open, substantially as described. 20

In testimony whereof I affix my signature in presence of two witnesses.

ALFRED J. ALLEN.
